WINDOW

Paul L. Adams, Dubuque, Iowa, assignor to Carr, Adams & Collier Company, Dubuque, Iowa, a corporation of Iowa

Application October 18, 1941, Serial No. 415,557

1 Claim. (Cl. 20—56)

The present invention relates to certain improvements in the construction of a window made from interconnected stiles and top and bottom rails. Such a window may take the form of a sash or a casement. For convenience, the ensuing description will refer to the window as a sash.

The improvements with which I am here concerned relate primarily to the joint that is provided between the connected rails and stiles. The joint in question will be shown and described in connection with the bottom rail.

For its objects my invention aims to provide a sturdy construction (1) in which the cross pins, driven at the joints, are adequately protected; (2) which can be produced with one less operation (with attendant economy) than is customary with the standard mortise and tenon joint; and (3) which permits, before assembly, of attachment of a weather strip to the bottom rail thereby making possible the shipment of the sash in knock-down condition with the weather strip pre-attached when the rails and stiles are to be assembled.

These and other objects, as will hereinafter appear, may be realized from a construction embodying my invention as illustrated in the accompanying drawing, wherein—

Figure 1 is a view in elevation of the exterior face of a window sash embodying my invention;

Figs. 2 and 3 are enlarged details in vertical sections taken, respectively, on lines 2—2 and 3—3 of Fig. 1;

Fig. 4 is a fragmentary detail in elevation of the lower end of a stile, looking toward the face thereof which confronts the rails with which it is associated;

Fig. 5 is an elevational view of one end of the bottom rail;

Fig. 6, which is a view in side elevation of one end portion of a bottom rail, shows in section the socket that is extended therein between the bases of the tenons; and

Fig. 7 is a view in perspective showing the lower end of one stile and one end of the bottom rail in the positions that they occupy when assembly is about to take place.

The sash herein shown is conventional to the extent that it comprises the usual four elements, viz., a pair of stiles S interconnected at opposite ends by top and bottom rails R in right angular relation thereto. The stiles and rails may be formed with any desired sticking so as to provide a shoulder 14 against which may be seated a pane 15 of glass or the like to be retained in

place as by a moulding 18, putty, or other appropriate means.

Through the bottom end of each stile is a slot 20, extending in a plane parallel to the associated bottom rail. Above this slot which is open along the bottom is a web 21 which separates the slot from a mortise 22 parallel thereto. The web provides a wall of substantial width extending between the slot and mortise. In practise, the shoulder section 14 remaining on the web is left undisturbed where it appears as a projecting end therefor (see Fig. 7).

A pair of stiles, each formed with a mortise separated from a slot which opens along the bottom, is adapted for interconnection with the bottom rail S from each end of which is extended a lower tenon 25 and an upper tenon 26 separated from each other by a distance which is equal to the spacing between the stile slot and mortise. The lower tenon 25 is of a size and shape so as to exactly fit within the stile slot 20, the other tenon being similarly formed to fit within the stile mortise 22, and both tenons desirably extending through to terminate flush with the remote face of the stile. When completely inter-fitted, the rail end will abut the stile, the web then occupying a position between the two tenons to extend partly between the base portions thereof as will shortly be pointed out.

The bottom side of the lower rail is shown as having a ratchet profile in that it comprises an inclined surface 39 extending inwardly and slightly upwardly from its outside face to terminate adjacent a depending shoulder 31 from the base of which is upwardly inclined a second surface 32 adapted to rest upon a sill 33 (see Fig. 3) when the sash is fitted within a window opening. Within the space between this sill and the bottom slanting surface 39 is received a weather strip 34, preferably of resilient material, shown as having one edge upwardly turned and then reversed as at 35 for frictional securing within a slot 36 that extends lengthwise of the bottom rail between the two ends thereof.

This slot which is in line with the rail tenons is extended centrally through the lower tenon 25 (see Figs. 2, 5 and 7). The weather strip which is secured within the slot may accordingly be extended for the full width of the sash with support afforded thereto for the full distance between its opposite ends.

It is possible to achieve certain economies in the production of a window sash as hereinbefore described. In practise, the bottom rail may be formed initially with a single wide tenon at each

end; this is then divided lengthwise into two tenons by a boring operation wherein is used a bit whose diameter is equal to the vertical dimension of the web 21. This bit is advanced into the bottom rail slightly beyond the base of the divided tenons, forming therebetween a socket 37 which extends shallowly into the rail. This socket is of a depth sufficient to receive the shoulder 14 which projects from the web 21; removal of the shoulder becomes unnecessary in consequence. It follows that, when assembly has taken place with the rail end abutting the stile, the shoulder will be closely fitted within the socket to engage with opposite walls thereof whereby to provide an enhanced resistance to relative movement between the rail and stile. The rail end may also be plowed as at 38 along one side of its two tenons at each end to accommodate the sticking on the stiles. Except for the usual sticking, tenoning and mortising operations, severance of the initial wide tenon by an advancing bit is the only extra operation required. On the other hand, it is unnecessary to relish the rail, or to plow back the shoulder on the stile to a depth equal to the depth of the usual stud which is left on the tenon after relishing. In other words, the production of a mortise and tenon joint, as ordinarily practised, requires two extra operations beyond the usual tenoning, sticking, and mortising, whereas the manufacture of the present joint requires only one extra operation, viz., the boring lengthwise through the initial wide tenon to produce two separated tenons for complementary interfitting with the mortise and slot of the stile.

When the sash elements have been assembled they may be locked in place as by pins 40 and 41 a pair of which is driven transversely through the sash in each corner, one passing through each of the two tenons and into the stile body therebeyond (see Fig. 3). Because each rail end is

formed with two tenons in spaced apart relation, these pins are, in consequence, well separated from each other. This is desirable because the shearing radius is thereby reduced considerably over what would obtain if a single tenon be used.

In practise, it has been found that a window sash produced in accordance with this invention is advantageous in the several respects that have already been noted. It offers definite economies in manufacture; it is stronger than the conventional types of sash; and it provides for the initial, but final, installation of a weather strip even before assembly of the sash elements takes place. This opens up new possibilities in the way of a factory-installed weather stripping in knock-down sash elements, ready for shipping to and assembly at a distant point close to the place of use.

I claim:

A window sash comprising a stile and rail adapted for interconnection in right angular relation, a pair of tenons in spaced edge to edge relation extending from one end of the rail with a socket between the tenons extending into the rail adjacent the base of the tenons and of a diameter to extend from one tenon to the other, the stile being formed therethrough with a mortise and a slot, the latter being open upon one end of the stile and the mortise and slot being separated from each other a distance equal to the spacing between the two tenons and each being sized to closely receive one tenon when the rail is assembled with the stile, a shoulder section projecting from the stile face proximate to the rail and of a length to fit the space between the tenons and projecting into said socket and closely engaging opposite walls thereof and providing enhanced resistance to relative movement between the rail and stile.

PAUL L. ADAMS.
